FURNITURE CONSTRUCTION

Myer Martin, Buffalo, N. Y.

Application March 14, 1931, Serial No. 522,653

4 Claims. (Cl. 155—179)

This invention relates to a resilient supporting construction for furniture, such as chairs, lounges, davenport, ottomans, and like pieces of furniture.

5 The cushion springs of such pieces of furniture are usually supported by cross webbing or by a sub-frame structure secured to the furniture frames. When webbing is used for this purpose, it is likely to tear away or stretch in use, causing 10 the seat to sag and to become uncomfortable to sit upon. The use of metal or wooden sub-frames of types heretofore employed materially increases the cost of the furniture and necessitates the use of resilient springs for supporting the sub-frame, 15 these springs being customarily disposed in a horizontal plane. At times when the furniture is excessively loaded or when the springs become stretched, through continued usage, the sub-frame and springs are likely to sag to a position 20 visible beneath the frame of the furniture. Cushion supporting springs, or cushion springs, mounted upon such sub-frames are likely to vibrate under flexure, as when loads are applied to the furniture, and sometimes co-act with the 25 sub-frame to set up annoying squeaks or other noises. The sub-frames must necessarily extend substantially over the entire seat area in order to adequately support all of the cushion springs and in some types heretofore used, have 30 comprised quite complicated net works of wire.

The present invention relates primarily to a sub-frame construction wherein a single plate or sheet of metal is used to support all of the cushion springs, and is resiliently supported by other 35 springs connected to the furniture frame. In order to minimize the requisite thickness of the metal plate, the supporting springs are attached to medial portions of the plate, and in order to avoid undue sagging of the sub-frame, which 40 might cause the sub-frame to become visible beneath the furniture frame, are inclined upwardly from the sub-frame whereby slight elongation of the supporting springs will result in a likewise slight sagging of the sub-frame. In 45 order to further strengthen the construction and to permit of a lighter sub-frame plate wire reinforcing means are disposed beneath the sub-frame and parts of this reinforcing means are extended upwardly to provide means for engaging the sub-frame supporting springs.

The present invention further comprehends a layer of fabric insulating material disposed along the upper surface of the metal plate of the sub-frame and between the sub-frame and the 55 cushion springs supported thereby to avoid

squeaks being set up by metal to metal contact of these parts. Means are also formed from the body of the metal plate to engage the insulating material to positively retain it in place and to engage the cushion springs to retain them in place.

These and other objects and advantages will become apparent from the following description of one typical embodiment of the invention, reference being made to the accompanying drawings wherein:

Fig. 1 is a plan view of an article of furniture embodying the features of construction of the present invention, portions thereof being broken away.

Fig. 2 is a side elevational view of the article shown in Fig. 1, portions thereof being broken away and being shown in section.

Fig. 3 is a fragmentary perspective view showing one corner of the construction illustrated in Figs. 1 and 2.

Fig. 4 is a perspective view of a complete sub-frame, other portions of the furniture construction being omitted.

Fig. 5 is a fragmentary vertical sectional view taken substantially along line 5—5 of Fig. 4 and depicting the construction of one edge of the sub-frame.

Fig. 6 is a vertical sectional view taken through a medial portion of the sub-frame substantially along line 6—6 of Fig. 4.

Fig. 7 is a detail partial sectional view through a part of the front portion of the main frame for a chair or the like showing supplemental supporting springs for the sub-frame to augment the coil springs.

As shown in the drawings, wherein an ottoman is depicted, the main frame 10 is of substantially rectangular form and extends substantially around the periphery of the article, being supported at its four corners by legs 11. Hooks 12, opening upwardly, are provided at spaced intervals about the entire inside periphery of the frame 10 and serve to secure the upper ends of coil springs 13 which resiliently support a sub-frame indicated generally at 14. The sub-frame includes a substantially rectangular plate 15 of contour similar to that of the frame 10. The marginal portions of the plate are return bent as indicated at 16 to overlie and positively retain a layer of burlap or other insulating material 17 which is extended across the upper surface of the plate.

A substantially rectangular loop of wire 18 for reinforcing the plate 15 extends therebeneath and

has formed thereon a plurality of upturned U-shaped sections or loops 18, which extend through apertures formed in the plate, and which are engaged by the lower ends of the springs 13 for supporting the sub-frame upon the frame 10. It will be noted that the sides of the reinforcing loop 18 are disposed a substantial distance from the margin of the plate 15 so that the area disposed within the loop 18 is substantially equal to the area between the periphery of the loop 18 and the periphery of the plate 15 so that cushion means disposed upon and supported by the sub-frame sheet will not impose undue strains upon any part of it.

15 Helical cushion springs 20 which are preferably of the double conical type, are disposed upon the upper surface of the sub-frame 14, being spaced from the plate 15 by the insulating material 17. Ears 21 are struck upwardly from the plate 15 and are bent over the lower convolutions of the helical cushion springs to secure them to the sub-frame structure. As shown in Fig. 1, the upper convolutions of the cushion springs are secured in the desired relation by 25 cross webbing 22 which may comprise strands of cord or wire. A rectangular wire frame or edge wire 23 also serves to join the upper convolutions of the outer or marginal cushion springs and generally defines the upper outline of the seat. 30 Conventional padding 24 is disposed on top of the springs and webbing and a covering 25 may be extended thereover and secured in any desired manner to the frame 10.

In the illustrated construction, where a single 35 cushion spring is supported by the plate 15 medially thereof, all of the remaining cushion springs being disposed marginally, the reinforcing loop is located only slightly inwardly of the axis of the marginal cushion springs, this disposition being 40 along a line which is the locus of the centers of the forces exerted by the downward pressures of all of the cushion springs, so that the total moment of forces about the line outwardly of the reinforcing loop will equal the total moment 45 of forces about the line inwardly of the loop. In the illustrated form therefore, the marginal springs will lie almost directly above the reinforcing wire, the latter in turn being supported by the springs 13 at points between adjacent 50 marginal cushion springs.

It will now be understood that the present invention provides a simple and durable sub-frame construction, the cushion springs being completely insulated from the one-piece sheet metal sub-frame base by the insulating material 17, whereby the occurrence of squeaks or other obnoxious noises is precluded. The marginal portions of the sheet insulating material are securely held in place by the return bent portions of the plate 15, and the medial portions are held in place by the upwardly extending loops 19 of the reinforcing member and by the ears 21, whose primary function is to retain the lower ends of the cushion springs. The springs 13, connected at 65 their lower ends to the loops 19, provide adequate support for the sub-frame structure and in turn, for the cushion springs, since the loops 19 are disposed at medial portions of the sub-frame.

The inclined relation of the springs 13 obviates 70 the likelihood of undue sagging of the sub-frame which would allow the springs 13 and the sub-frame to become visible beneath the frame 10, since slight elongation of the springs 13 can produce only a correspondingly slight sagging of

the sub-frame structure. This inclined relation of the springs 13 also permits of the use of lighter sub-frame supporting springs than would be possible with springs disposed in a horizontal plane.

It has been found in practice that the front of the plate at the front of a chair or other similar piece of furniture may have a tendency to sag slightly, due to persons using the furniture and sitting on the front edges of the seat. This will place most of the weight on the helical springs 10 disposed along the front side of the frame and with constant use in this way this sagging may become apparent. In order to obviate such difficulty in chairs and the like additional coil springs 13 may be used at the front of the piece 15 of furniture. It has also been found desirable to use small coil springs 26 in place of adding additional springs 13 in which the springs 26 are connected to the front edge of plate 15 and to the adjacent portion of frame 10 by means 20 of hooks 27 as shown in Fig. 7. This will serve to maintain a proper support and balance for the sub-frame.

It will further be understood that the article herein described is merely illustrative of the 25 principles of the invention and that these principles may be utilized in other articles of furniture having different structural forms and different structural relationships.

What is claimed is:

1. In a furniture construction, a substantially rectangular frame, a sheet metal cushion supporting member disposed within the confines of said frame, a wire reinforcing unit disposed beneath said sheet metal member and embracing 35 medial portions thereof, and a plurality of springs connecting said wire reinforcing member to said frame for supporting the wire and sheet metal member as a unit, said springs being inclined downwardly from said frame to said reinforcing 40 member, and a plurality of cushion springs supported by said metal member.

2. In a furniture construction, a substantially rectangular frame, a metallic plate disposed centrally of said frame, reinforcing means extending beneath and engaging medial portions of said plate, loops formed on said reinforcing means and extending upwardly through said plate, and spring means connecting the frame and said loops.

3. In a sub-frame construction for articles of furniture, a sheet metal plate, a reinforcing loop of wire disposed beneath said plate and engaging medial portions thereof, upwardly bent U-shaped sections formed on said reinforcing loop and extending through apertures formed in said plate for providing means to be engaged by springs for supporting the sub-frame construction.

4. A cushion supporting sub-frame for furniture constructions comprising a sheet metal plate of area substantially equal to the area of the cushion, a wire reinforcing loop disposed beneath said metal plate, loops formed on said reinforcing member and extending upwardly through apertures formed in said plate, a layer of insulating material disposed upon the upper surface of said plate, and ears struck out from said plate for engaging cushion springs and extending through said layer of insulating material, the marginal portions of said metal plate being return bent to engage over the marginal portions of said layer of insulating material.
